US00D902332S

(12) **United States Design Patent** (10) Patent No.: **US D902,332 S**
Kruse et al. (45) Date of Patent: **** Nov. 17, 2020**

(54) **TREADMILL DECK**

- (71) Applicant: **Peloton Interactive, Inc.**, New York, NY (US)
- (72) Inventors: **Mark Kruse**, Brooklyn, NY (US); **Jason Poure**, Hastings on Hudson, NY (US); **Nigel John Alcorn**, Brooklyn, NY (US); **Lee Hendrickson**, Brooklyn, NY (US)
- (73) Assignee: **Peloton Interactive, Inc.**, New York, NY (US)
- (**) Term: **15 Years**
- (21) Appl. No.: **29/724,262**
- (22) Filed: **Feb. 13, 2020**

Related U.S. Application Data

- (62) Division of application No. 29/692,629, filed on May 28, 2019, now Pat. No. Des. 875,856, which is a division of application No. 29/632,278, filed on Jan. 5, 2018, now Pat. No. Des. 854,101.

CLAIM

The ornamental design for a treadmill deck, as shown and described.

DESCRIPTION

FIG. 1 is a front perspective view of the treadmill deck, showing our new design.

FIG. 2 is a back perspective view thereof;

FIG. 3 is a front view thereof;

FIG. 4 is a back view thereof;

FIG. 5 is a left-side view thereof;

FIG. 6 is a right-side view thereof;

FIG. 7 is a top view thereof; and,

FIG. 8 is a bottom view thereof.

The broken lines depict portions of the treadmill deck and/or environment of the treadmill deck that form no part of the claimed design.

1 Claim, 8 Drawing Sheets
